SOUND PROPAGATING DEVICE

Clair L. Farrand, Larchmont, Mamaroneck, N. Y., assignor to Radio Corporation of America, a corporation of Delaware

Application December 11, 1937, Serial No. 179,224

3 Claims. (Cl. 181—27)

This invention relates to loudspeakers and particularly to the sound radiating portion thereof. This application is a division of my copending application Serial No. 94,072, filed August 3, 1936, in which the translating unit disclosed herein is being claimed.

It is well known in the art to allocate a part of the acoustic range of a sound reproducing apparatus to one type of loudspeaker and another part 10 or parts to another type (or other types) of loudspeaker.

This invention relates to the type of loudspeaker useful in a so-called two-way system, wherein the acoustic range is handled by only two 15 types of loudspeakers, the type of loudspeaker of the present invention being particularly adapted to reproduce acoustic frequencies from about three hundred cycles to the upper limit, i. e., eight thousand cycles or higher.

The objects of the present invention comprise an efficient reproduction of sound waves over a wide frequency range, with large power, and while attaining a substantially uniform distribution of the sound waves, particularly of the higher frequencies which have a tendency to remain in a narrow beam.

The novel features of one embodiment of the invention will be described in the accompanying specification, and particularized in the appended claims in connection with the accompanying drawings, wherein:

Figure 1 is a sectional elevational view of a loudspeaker embodying the present invention.

Figure 2 is an enlarged fragmentary sectional view of the annular diaphragm and the accompanying sound chamber forming parts.

Figure 3 is a front view looking toward the mouth portions of the nested horn assembly.

Figure 4 is a plan sectional view through the throat block and is taken along the line 4—4 of Fig. 1.

Figure 5 is a sectional plan view through the lower set of diaphragm clamping rings and is taken along the line 5—5 of Fig. 1, and

Figure 6 is a bottom plan view of a portion of the annular diaphragm showing the connection of the voice coil thereto.

Referring now to Figs. 1 and 5, the driving unit 1 of the loudspeaker comprises a U shaped magnetic frame 2, having a central core 3 of magnetic material secured thereto. A circular plate 4, comprising an inner pole piece, is provided on the upper surface of the core 3, and this assembly, including the frame 2, core 3, and pole piece 4, is secured together by means of

a bolt 5. An annular plate 6, comprising an outer pole piece, is secured to the magnetic frame 2 by means of bolts 7, with its inner edge concentric with and closely adjacent to the outer edge of the inner pole piece 4. An electro-magnetic coil 8 is provided around the core 3, and receives a supply of direct current so as to produce a constant magnetic flux between the two separated pole pieces 4 and 6.

As will be noted in Fig. 2, the adjacent outer and inner edges of the pole pieces 4 and 6, respectively, are undercut as at 10, leaving only a short length of parallel, closely adjacent pole faces at 11. The space thus provided between the parallel faces 11 of the pole pieces 4 and 6 accommodates the voice or driving coil 12 of an annular diaphragm 13. The diaphragm 13 is supported below its inner and outer edges by means of inner and outer concentric supporting rings 14 and 14¹, respectively. Upper concentric clamping rings 15 and 16 clamp the edges of the diaphragm upon the supporting rings 14 and 14¹ by means of bolts 17.

A frusto-conical member 18, with a coextensive conical member 19, secured together and to the upper surface of the inner clamping ring 15 by means of bolts 20 and the central bolt 5, and a casing member 21, all concentric with the diaphragm 13, form an annular sound passage 22 leading to the central portion of the annular diaphragm 13.

The annular sound passage 22, at the tip of the conical member 18, communicates with a tubular passage 23 formed in an adapter 24. This passage 23 is coextensive with a similar passage 25 formed in a throat block 26.

Adapter 24 is fitted in a counter-bored portion on the top of the casing member 21, and has an annular shoulder portion 24¹ which is engaged by a locking nut 27 threadably secured to the casing member 21. The throat block 26 is threadably secured at 26¹ to the upper portion of adapter 24. The upper portion of the throat block 26 is formed in a funnel shape having diverging flanges 28, so as to receive the throat portions of a plurality of horn sections 29 to 44, inclusive. A suitable cement 34 is provided to secure the throat portions of the various horns together between the flanges 28 of the throat block 26. These various horns are all identical in shape and size, having their longitudinal axes diverging from each other away from their throat portions. This arrangement of nested horn sections eliminates the well known directional or beam effect of the higher frequencies by means of the ap-

proximate spherical surface formed by the combined mouth opening 45 thereof. That is, in the case of a spherical source of sound, such as a diaphragm in the shape of a sphere, the surface of which vibrates radially in accordance with the frequency and amplitude at every point thereon, sound would be radiated through the entire frequency range, including the higher frequencies, in all directions. In case, however, the source 5 from which the sound is radiated constitutes only a segmental portion of a sphere, this uniform sound radiation would still prevail through the solid angle subtending the segmental surfaces and the center of curvature thereof. This condition is approximated by the nested horn assembly 29 to 44, inclusive, by angularly disposing the longitudinal axes thereof so as to form at their combined mouth opening a spherical segment from which the sound is radiated into the atmosphere. It will thus be seen that the individual 10 sound waves propagated in the various horns will have exactly the same characteristics and will be so timed that they will unite at the combined mouth opening to form a spherical wave front. The combined throat opening 46 of the various horns 29 to 44, inclusive, is also in the shape of a spherical segment. Preferably, the height of the segmental surface thus formed, as indicated by the dimension "A", between the single throat 15 opening of the center horn 43 and the chordal line passing through the throat portions of the outer horns 29 and 35 (Fig. 1) is of the order of one-quarter wave length of the highest frequency sound to be reproduced so as to prevent distortion 20 and/or cancellation of a nearly planar wave front 25 on entering the combined throat opening 46 and emerging from the combined mouth opening 45. It will be seen, therefore, that since all of the horns are of the same length, intersection "B" 30 of the longitudinal axes of the horns also forms the center of curvature for both the combined throat openings 46 and the combined mouth 35 openings 45.

As will be seen in Fig. 3, the combined throat 40 portion as indicated by the dotted line 46¹ is rectangular in shape and opens into the sound passage 25 of the throat block 26, which is of the same rectangular shape and size in cross-section 45 at its upper end (Fig. 4). The passage 25 and the coextensive passage 23 in the adapter 24 gradually change in cross-sectional shape until they 50 assume a substantially circular cross-section adjacent the tip of the plug 16.

Preferably, the annular passage 22, tubular 55 passages 23 and 25, and the passages forming the various individual horns 29 to 44, inclusive, have an exponential rate of taper or exponential rate of cross-sectional increase along the lengths thereof, increasing from the throat to the mouth 60 portions thereof, this rate being the same throughout. The size of these various passages is determined by the upper and lower frequency limits. For example, the size of the throat opening of the annular passage 22, adjacent the diaphragm 13, is determined by the amount of air 65 velocity change between the diaphragm chamber and the annular passage 22. The limiting factor in making the throat of passage 22 as small as possible is the frictional resistance of the air 70 with the walls of passage 22 when moving at the increased velocity and the harmonic distortion which results when the instantaneous pressures depart too far from atmospheric pressure. The 75 number of horns is determined by the solid angle through which the sound, particularly of the

higher frequencies, is to be distributed. In the present case (Fig. 3), the horns are arranged in five vertical rows with three horns in each row. This particular arrangement of horns, however, may be varied to suit the conditions of the particular auditorium or theatre in which the loudspeaker is to be placed. The length and rate of taper of the various horns is determined by the lowest frequency sound to be reproduced and are preferably such that the smallest dimension of 10 the combined mouth opening of the various horns is on the order of one half of the wave length of the lowest frequency to be radiated.

Referring to Fig. 2, it will be noted that the annular diaphragm 13, which in the present case 15 is constructed of duralumin of the order of .002 inch in thickness, comprises, in radial cross-section, an annular trough 46, with relatively smaller annular corrugations 47 and 48 on either side thereof. These corrugations 47 and 48 increase 20 the flexibility at the edge to allow the annular trough portion 46 to be reciprocated as a rigid section by the voice coil 12. The sound chamber or sound box 49, as defined by the upper surface of the diaphragm 13 and the lower surface of 25 the ring 16 and member 18, closely follows the contour of the cross-sectional shape of diaphragm 13. That is, the under surfaces of the ring 16 and member 18, directly above the active portion of diaphragm 13, are similar in shape to 30 the cross-sectional form of the annular trough 46 and corrugations 47 and 48. However, the curvature of the bottom surfaces of the ring 16 and member 18, directly opposite the trough portion 46, and which extend thereinto, is slightly less 35 than that of this trough portion.

The distance from the annular throat opening 55 of the annular passage 22 to the inner and outer edges of the diaphragm sound chamber 49, or in other words, to the supported edges of the 40 diaphragm 13, is of the order of one-quarter wave length of the highest frequency sound intended to be reproduced. In the present case, the dimension is about 0.4 inch. Thus, there will be no undue cancellation of a sound wave of 8000 45 cycles generated in the chamber 49 due to the difference between the time required for a wave originating at the extreme inner or outer edge of the diaphragm 13 to enter the sound opening 55 and the time required for a corresponding wave 50 generated at the central portion of the trough 46 of diaphragm 13 to enter the same sound opening 55. If, for example, this distance between the supported edges of diaphragm 13 and the opening 55 were as great as one-half the wave 55 length of the highest frequency sound intended to be reproduced, a wave originating at the furthest point in the chamber 49 would be 180° out of phase with a wave originating at a point directly opposite the opening 55 and therefore the 60 two waves would cancel each other.

Referring to Figs. 2 and 6, the voice coil 12 is secured to the central portion of the annular trough 46, directly below the annular sound passage 22. This construction allows the driving 65 force, i. e., the coil 12, to be directly in the center of the plunger section, i. e., the trough 46 of diaphragm 13, and also directly in line with the exit of sound through the passage 22.

As will be noted in Figs. 2 and 6, the driving 70 or voice coil 12 is secured to the central portion of diaphragm 13 by means of a cylindrical support 56 of cardboard or the like material around which coil 12 is wound. One edge of the support 56 is serrated with alternate serrations 57 and

- 58, etc., extending on the same side, horizontally, to form a base which may be cemented or otherwise secured to the under surface of the annular trough portion 45.
- 5 Vents 58 (Figs. 2 and 5) in the form of a plurality of holes arranged in a concentric path about the diaphragm 13 are provided in the inner pole piece 4 to communicate the inner back chamber 60, formed between the back surface of diaphragm 13, pole piece 4, and ring 14, with the outer atmosphere. A second series of vents in the form of radial slots 61, provided in the diaphragm supporting ring 14¹, communicate the outer back chamber 62, formed by the back surface of diaphragm 13, outer pole piece 6 and ring 14¹, with the outer atmosphere. These two series of vents thus assist the very narrow spaces between the voice coil 12 and the adjacent inner and outer edges 11 of the pole pieces 6 and 4, respectively, in relieving the damping effect on the diaphragm due to the practically enclosed back chambers 60 and 62.

I claim as my invention:

1. An acoustic device comprising a plurality of

nested horns of equal length and identical shape, the inlets to said horns being arranged on a curve concentric with the curve upon which the outlets of said horns are arranged, the distance from the inlets of the center horns to a chord connecting the inlets of the outer horns being of the order of one-quarter of the wave length of a frequency at least as high as 8000 cycles.

2. An acoustic device in accordance with claim 1 in which the area of each of said horns increases logarithmically from their inlets to the respective outlets thereof.

3. An acoustic device comprising a plurality of nested horns of equal length and identical shape, the inlets to said horns being arranged on a curve concentric with the curve upon which the outlets of said horns are arranged, the distance from the inlets of the center horns to the center of a chord connecting the outermost horn inlets being of the order of one-quarter of the wave length of the highest frequency to be transmitted through said horns.

CLAIR L. FARRAND.
